UNITED STATES PATENT OFFICE.

CHARLES F. WALTHER, OF BUFFALO, NEW YORK.

DESIGN FOR A RADIATOR-LOOP.

SPECIFICATION forming part of Design No. 23,914, dated December 25, 1894.

Application filed October 12, 1894. Serial No. 525,726. Term of patent 7 years.

To all whom it may concern:

Be it known that I, CHARLES F. WALTHER, a citizen of the United States, residing at Buffalo, in the county of Erie and State of New York, have invented a certain new and original Design for a Radiator-Loop; and I do hereby declare the following to be a full, clear, and exact description of the invention, such as will enable others skilled in the art to which it appertains to make and use the same.

My new and original design has for its object to impart to a loop for a steam or hot water radiator a novel and pleasing configuration.

The design is illustrated in the accompanying drawings, wherein—

Figure 1 is an elevation of a radiator loop embodying my design, and Fig. 2 is a transverse sectional view on the line 2—2 of Fig. 1.

The flues through which the heating medium circulates are separated from each other by the spaces 2, 2, forming the columns; the end columns being designated 3, 3 and the intermediate column, 4.

25

The essential characteristic of my design consists in the novel shape which I give to the intermediate column, which is separated from and is wider than the end columns and is fluted in the direction of its length, the flutes being separated by the ridges 5.

What I claim is—

The design for a radiator loop, substantially as shown and described.

In testimony whereof I affix my signature in presence of two witnesses.

CHARLES F. WALTHER.

Witnesses:

FRANK C. PEREW,
WM. J. HANRAHAN.
